UNITED STATES PATENT OFFICE.

HOWARD H. McMULLEN, OF BROOKLYN, NEW YORK, ASSIGNOR TO THE IDEAL AUTOMATIC PUMP GOVERNOR COMPANY, OF NEW YORK, N. Y., A CORPORATION OF NEW JERSEY.

SOLDERING-IRON.

No. 839,506.

Specification of Letters Patent.

Patented Dec. 25, 1906.

Application filed January 20, 1906. Serial No. 296,923.

To all whom it may concern:

Be it known that I, HOWARD H. McMULLEN, a citizen of the United States, residing at Brooklyn, in the county of Kings and State of New York, have invented certain new and useful Improvements in Soldering-Irons, of which the following is a specification, such as will enable those skilled in the art to which it appertains to make and use the same.

10 This invention relates to soldering-irons; and the object thereof is to provide an improved device of this class which is simple in construction and convenient of manipulation and which is provided with a reservoir or receiver for soldering material which may be melted when desired for use and gradually fed as desired to the operating-point of the soldering-head of the instrument.

The invention is fully disclosed in the following specification, of which the accompanying drawings form a part, in which the separate parts of my improvement are designated by suitable reference characters in each of the views, and in which—

25 Figure 1 is a longitudinal section of my improved soldering-iron; Fig. 2, a plan view of a detail shown in Fig. 1; and Fig. 3, a view of the handle construction shown in Fig. 1, but showing the parts in a different position.

30 In the practice of my invention I provide an oblong hollow receiver *a*, preferably tubular in form and into one end of which is screwed the soldering-head *b*. The opposite end of the receiver *a* is closed by a hollow screw-threaded plug *c*, through which is passed a tube *d*, provided with a head *d*², which is secured in the plug *c*, and the tube *d* is adapted to bear on the inner end *b*² of the soldering-head *b* and is provided in the top and bottom of said 40 end, or in the opposite side thereof, with recesses *d*³.

Secured in the head *d*² of the tube *d* is a tubular handle member *e*, to which is secured a handle *f*. The handle *f* is composed of two parts, the outer part *f*² thereof being secured to the inner part by screws *f*³, and formed in the outer part *f*² of the handle *f* is a chamber *f*⁴, and a valve-rod *g* is passed through the tubular handle member *e* and through the tube *d* and into the chamber *f*⁴ of the handle *f*, and secured to the end of the valve-rod *g* is a collar or similar device *g*², and at a predetermined distance therefrom is another collar *g*³,

between which and the collar *g*² is placed a spiral spring *g*⁴, and the collar *g*³ is held in place by a pin *g*⁵. The spring *g*⁴ serves to force the valve-rod *g* normally forwardly, and the front end of said valve-rod is adapted to close the longitudinal bore or passage *b*³ in the soldering-head *b*, said valve-rod operating as a needle-valve for this purpose.

In front of the handle *f* the tubular handle member *e* is provided with a longitudinal slot *h*, through which is passed a screw *h*², preferably provided with a large detachable head *h*³, beveled forwardly and downwardly, as shown at *h*⁴, and the inner end of said screw *h*² is connected with or secured in the valve-rod *g*.

The receiver *a* is provided in one side thereof with a filling-opening *a*², closed by a threaded plug or similar device *a*³ and through which in practice the soldering material may be passed.

In practice the soldering material is poured into the receiver *a* while in a melted condition, or said soldering material may be finely divided and passed into the receiver *a* through the opening *a*² without being melted, and whenever it is desired to use the device the receiver *a* is held over a charcoal or other fire until the soldering material therein is in a liquid condition. The operator then grasps the handle *f* and by means of the thumb or one of the fingers pulls back the slide formed by the screw *h*² and the head *h*³ thereof. This operation forces the valve-rod *g* backwardly and opens the port or passage *b*³ in the soldering-head *b*, and the device may be used in the same manner as other devices of this class, 90 the soldering material in this operation passing through the bore *b*³.

It will be understood that the spring *g*⁴ normally holds the valve-rod *g* in such position as to close the port or passage *b*³, and whenever the operator desires to use the device for soldering or similar purposes the valve-rod *g* must be moved back, as hereinbefore described.

Having fully described my invention, what I claim as new, and desire to secure by Letters Patent, is—

1. A soldering-iron comprising a receiver, a soldering-head screwed into one end thereof, a hollow plug screwed into the other end thereof, a tube mounted in said hollow plug

and extending through the receiver, a tubular handle member connected with said tube, a valve-rod passing through said tubular handle member and through said tube into said receiver and adapted to close the bore or passage through the soldering-head, a handle connected with the end of the tubular handle member, a spring placed in said handle for forcing the valve-rod forwardly, and means whereby the said valve-rod may be moved backwardly.

2. A soldering-iron comprising a receiver, a soldering-head connected with one end thereof, a hollow plug detachably secured in the other end thereof, a tube mounted in said plug, a tubular handle member connected

with said tube, a handle connected with the tubular handle member and composed of separate parts, a valve-rod passing through said tubular handle member and through said tube into and through the receiver, a spring in the handle for forcing the valve-rod forwardly, and means for drawing the valve-rod backwardly.

In testimony that I claim the foregoing as my invention I have signed my name, in presence of the subscribing witnesses, this 18th day of January, 1906.

HOWARD H. McMULLEN.

Witnesses:

F. A. STEWART,
C. J. KLEIN.

Correction in Letters Patent No. 839,506.

It is hereby certified that Letters Patent No. 839,506, granted December 25, 1906, upon the application of Howard H. McMullen, of Brooklyn, New York, for an improvement in "Soldering-Irons," were erroneously issued to "The Ideal Automatic Pump Governor Company," as owner of the entire interest in said invention; whereas said Letters Patent should have been issued to the inventor *Howard H. McMullen and The Ideal Automatic Pump Governor Company, jointly*, said Company being the assignee of *one-half* interest only in said patent, as shown by the record of assignments in this office; and that the said Letters Patent should be read with this correction therein that the same may conform to the record of the case in the Patent Office.

Signed and sealed this 29th day of June, A. D., 1909.

C. C. BILLINGS,
Acting Commissioner of Patents.

and extending through the receiver, a tubular handle member connected with said tube, a valve-rod passing through said tubular handle member and through said tube into said receiver and adapted to close the bore or passage through the soldering-head, a handle connected with the end of the tubular handle member, a spring placed in said handle for forcing the valve-rod forwardly, and means whereby the said valve-rod may be moved backwardly.

2. A soldering-iron comprising a receiver, a soldering-head connected with one end thereof, a hollow plug detachably secured in the other end thereof, a tube mounted in said plug, a tubular handle member connected

with said tube, a handle connected with the tubular handle member and composed of separate parts, a valve-rod passing through said tubular handle member and through said tube into and through the receiver, a spring in the handle for forcing the valve-rod forwardly, and means for drawing the valve-rod backwardly.

In testimony that I claim the foregoing as my invention I have signed my name, in presence of the subscribing witnesses, this 18th day of January, 1906.
